UNITED STATES PATENT OFFICE

99,747

DESIGN FOR A DILATOR OR SIMILAR ARTICLE

August Greth, Los Angeles, Calif.

Application January 13, 1936, Serial No. 60,562

Term of patent 14 years

To all whom it may concern:

Be it known that I, August Greth, a citizen of the United States and resident of Los Angeles, in the county of Los Angeles, State of California, have invented a new, original, and ornamental Design for a Dilator or Similar Article, of which the following is a specification, reference being had to the accompanying drawing, forming part thereof.

In the drawing:

or similar article embodying my new design; and Figure 2 is an end view thereof.

I claim:

The ornamental design for a dilator or similar article, substantially as shown.

In testimony whereof, I have signed my name to this specification.

AUGUST GRETH.
